UNITED STATES PATENT OFFICE.

JULE SCREVEN WILLCOX, OF SAVANNAH, GEORGIA.

DEVICE FOR MELTING SOLIDS.

Application filed December 22, 1922. Serial No. 602,507.

To all whom it may concern:

Be it known that I, JULE SCREVEN WILLCOX, a citizen of the United States, residing at city of Savannah, in the county of Chat-

ham and State of Georgia, have invented cer-
tain new and useful Improvements in De-
vices for Melting Solids, of which the fol-
lowing is a specification.

My invention relates to devices for melt-
ing solids and more particularly to that class
of devices used for melting sealing wax and
similar materials.

An object of my invention is to provide
a device which will quickly and easily heat
a charge of sealing wax and permit a por-
tion of said charge to be evacuated while at
the same time the device may be held steady
by supports attached to the device.

Another object of my invention is to pro-
vide efficient manually controlled means
whereby the flow of melted material from
the discharge opening may be prevented or
regulated.

A still further object of my invention is
to provide a device having a removable
handle which may be readily detached to
permit the insertion of a charge in the oven.

Another object of my invention is to pro-
vide a device carrying a sealing stamp which
is continually and automatically kept clean
and which, when not in use, operates to cause
the stoppage of the flow of melted material
from the discharge opening.

Another object is to provide a device hav-
ing exterior and interior plugs for the dis-
charge opening, both of which may operate
simultaneously, with means whereby they
are both held in normal inoperative position.

One of the main objects of this invention
is to provide a structure which is simple to
make, sturdy and easy to repair and in
which there are few parts to get out of order.

With these and other objects in view
which may be incident to my improvements,
the invention consists in the parts and com-
binations to be hereinafter set forth and
claimed, with the understanding that the
several necessary elements comprising my
invention, may be varied in construction,
proportions and arrangement, without de-
parting from the spirit and scope of the ap-
pended claims.

In order to make my invention more clearly
understood, I have shown in the accom-
panying drawings means for carrying the
same into practical effect, without limiting

the improvements in their useful applica-
tions to the particular constructions, which
for the purpose of explanation, have been
made the subject of illustration.

60

In the drawings:

Figure 1 is a view in side elevation of
my device;

Fig. 2 is a view partially in longitudinal
section taken through the axis of my device.

65

Fig. 3 is a view in longitudinal section
taken on line 3—3 of Fig. 1;

Fig. 4 is a cross-sectional view taken on
the line 4—4 of Fig. 1, looking in the di-
rection of the arrows;

70

Fig. 5 is a cross-sectional view taken on
the line 5—5 of Fig. 2, looking in the di-
rection of the arrows;

Fig. 6 is a cross-sectional view taken on
the line 6—6 of Fig. 3 looking in the direc-
tion of the arrows;

75

Fig. 7 is an end view of my device;

Fig. 8 is a detail of the oven construction
showing the distribution of the resistance
element.

80

My device comprises a heating vessel
formed of electrical insulating material and
having at one end a discharge opening. In
proximity to the discharge opening is lo-
cated an electrical resistance element wound
in double spirals in grooves on the heating
vessel. Over the resistance material is a
layer of heat and electric insulating ma-
terial, which latter is covered by a shell. A
detachable handle forms the base of the heat-
ing chamber, and exterior and interior plugs
closing a discharge opening are controlled
by a mechanism in the handle. A sealing
stamp mechanism is rotatively mounted near
the discharge opening at a point adjacent
short supporting legs, and a cam on the
mounting for the sealing stamp cooperates
with mechanism to shut off the flow of melt-
ed material from the discharge opening dur-
ing the stamping operation.

95

Referring to the detailed drawings for a
more careful description, I have shown a
device comprising an outer shell 1, pref-
erably of metallic construction in which is
adapted to fit at one end a handle 2. Within
the outer casing 1 is a lining of material
3 which is both a non-conductor electrically
and a poor conductor of heat. A short an-
nular portion 4 of this non-conducting layer
3 is removably placed at one end for the
purpose of making adjustments and for re-
moving the parts.

105

110

Within the non-conducting layer 3 is a heating vessel 5, preferably of electrically non-conducting material and having at one end, which I designate the oven, a heavy double spiral groove 6 within which is placed an electric resistance element 7. The element is wound in the double spiral grooves so that the conductors 8, which lead up from one end of the heating vessel to the portion which has the spiral grooves 6 therein, are of even length.

Near the outer extremity of the oven end of the heating vessel 5 I have provided screw-threads 9 which coact with screw-threads 11 of the casing 1 to hold the heating vessel in place. I have provided the oven end of the heating vessel with a conically tapered portion 12 and a discharge opening 13. Through the walls of the heating vessel 5, the annular portion 4 of the insulating layer and the outer shell 1, I have drilled a hole which is screw-threaded and provided with a screw-threaded tap 14, having an opening 15 therein. This opening acts as a vent for the escape of gases produced in melting the substance placed in the heating vessel. By unscrewing the tap 14 the heating and insulating material may be readily removed from the outer shell 1.

The handle 2 fits within the casing 1 and its upper portion 16 fits against the lower end of the short annular portion 4 of the non-conducting layer 3, and against the lower end of the heating vessel 5. The upper portion 16 of the handle 2, therefore, forms a base for the heating vessel. A protecting tube 17 is screwed at 18 into the portion 16 of the handle 2.

Adapted to reciprocate within the protecting tube 17 is a stem 19 upon which is mounted a ball or plug 21 which may be used to close from the inside the discharge opening 13 of the oven. Below the portion 16 of the handle 2 and on the stem 19 is a lug 22 against the upper side of which bears a compression spring 23 whose upper end bears against the heating vessel base 16. This compression spring normally keeps the plug 21 in the position shown in Fig. 3, that is, withdrawn from the discharge opening 13. Should the plug 21 be in a position to block up the discharge opening 13, upon heating of the material within the oven the material will soon become soft enough to permit the compression spring 23 to withdraw the plug 21 from the discharge opening. The protecting tube 17 prevents injury to the stem 19 in its reciprocating movement within the oven.

Below the lug 22 on the stem 19 is located another compression spring 24. A stop button 25 prevents the compression spring 24 from slipping off the stem 19. A lever 26 includes between its forked ends 27 the stem

19, and the compression spring 24 is adapted to bear at its lower end against the forked ends 27 of this lever. The lever is pivoted on a support member 28 by means of a rocking pin 29. The support member 28 is firmly held within a tubular guide 31 whose lower end rests against shoulders 32 formed on an annular opening in the handle 2. The upper end of the lever 26 is pivotally connected through a rocker pin 33 to a thumb button 34. A hole 34' in the thumb button in the down position of the button is adapted to lie opposite a hole 35' in the tubular guide. By inserting a suitable pin through holes 34' and 35' the thumb button 34 may be held in the down position.

Preferably integrally formed with the thumb button 34 is a lever arm 35 which is pivoted by means of a rocker pin 36 to an upstanding support 37 firmly seated within an aperture 38 in the handle 2. The lever 35 is provided with an upstanding arm 39 to which is pivotally connected by means of a rocker pin 41, a rod 42, adapted to reciprocate in a direction substantially parallel to the longitudinal axis of the heating vessel.

The reciprocating rod 42 is bent at 43 and provided at its upper extremity with a plug 44 which is adapted to seat against the exterior of the discharge opening 13 to shut off the flow of melted material. The rod 42 reciprocates freely through an outstanding support arm 45 which may be integrally formed with the casing 1. Mounted on the rod 42 at a point slightly below the support arm 45 is a cam member 46 through which the rod may be reciprocated, in a manner to be described, irrespective of any manual pressure on the thumb button 34. Adapted to fit around the casing 1 is a holder member 47. One side of the holder member 47 passes through a slot 48 in the support arm 45, and the other part of the holder member 47 passes down under the other side of the casing 1 and is adapted to fit over an outstanding lug 49, which passes through an aperture 51 in the holder member 47. At its lower extremity the holder member 47 terminates in two short legs 52. The upper part of the holder member 47 is provided with carriers and a clamping mechanism 53 in which is held a cleansing sponge 54.

On the outstanding lug 49 is pivoted an arm 55 and pivoted on a lug 56 of the support arm 47 is an arm 58. The arm 58 is provided with a cam 59 which is adapted to cooperate with the cam member 46 of the reciprocating rod 42. The arms 55 and 58 are fastened at their upper extremities to a handle 61 by means of a pivot pin 62 upon which the handle 61 is rotatively mounted. The handle 61 is provided with a sealing stamp 63.

In order to lead the current into the leads 8 of the heating vessel, the leads 8 are provided at their termini with contact members 64. The handle 2 is provided with two annular pockets 65 therein carrying conductor compression spring 66 whose upper ends are adapted to bear against the contact members 64. The lower ends of the conductor springs 66 contact at their lower ends with conductor terminals 67.

The conductor terminals 67 constitute the ends of conductors 68 which are consolidated into the lead-in wire 69, that lies within an aperture 71 within the center of the handle 2. This aperture 71 acts also as a housing for the end of the stem 19.

The lead-in wire passes through a central aperture 72 within a screw plug 73 placed at the lower end of the aperture 71. The screw plug 73 is formed with a supporting member or ring 74 by which the device may be hung on a suitable hook when not in use. The lead-in wire 69 is provided with a screw socket 75. A snap switch 76 may be located near the handle 2 for convenience in turning the current on or off.

In use the heating vessel 5 is filled with a suitable quantity of sealing wax or any other material by removing the handle 2. The handle 2 is then slipped into place and the conductor compression springs 65 close the circuit through the screw socket 75, the snap switch 76, the conductors 68 and the resistance coils 7. Should the interior plug 21 be stuck fast within the discharge aperture 13 in the oven, the melting of the material in proximity to the aperture 13 will permit the compression spring 23 to withdraw the plug 21 from the aperture. Should

it be found desirable to close the aperture 13, a pressure on the thumb button 34 will act through the lever 26 to cause the arms 27 to press on the compression spring 24, which will overcome the pressure of the compression spring 23 and cause the longitudinal plug 21 to close the discharge aperture 13. By reason of the fact that the pressure of the thumb button 34 is exerted through a spring 24, damage caused by undue strains and sticking of the plug in the material within the oven, is avoided. At the same time lever arm 39 is rocked to cause rod 42 to reciprocate to close the aperture 13 with the external plug 44. When the thumb button occupies the down position, a pin may be inserted through apertures 34' and 35' and the discharge aperture 13 will remain closed.

In the stamping operation the legs 52 steady the device while pouring the sealing wax. The sealing stamp 63, constantly kept clean by means of the wiping sponge 54, is rotated down into the position shown in Fig. 2 to stamp the impression on the sealing wax. At the same time the cam 59 operates on the

cam member 46 of the rod 42 to reciprocate the rod in a backward direction. This operates through arm 39, through arm 35 and through lever 26 to transmit motion to the stem 19 to close the discharge aperture 13 from the interior. The backward reciprocation of the rod 42 causes the exterior plug 44 to close the discharge aperture 13 from the exterior. Therefore, in each stamping operation the aperture 13 is closed both from the exterior and the interior. As has been previously explained, this sealing of the discharge aperture 13 may be accomplished by pressure on the thumb button 34, irrespective of the sealing operation.

I have described a device in which the operation of closing the discharge vent may be accomplished either automatically or at will. Though I have shown the closing of the discharge aperture as accomplished both from the exterior and the interior simultaneously, either of these mechanisms for accomplishing the exterior and the interior closure may be utilized alone and will operate efficiently. The unique way of winding the resistance on the oven, the means for continuously keeping the sealing stamp clean, and the other advantageous features of my device give it a high degree of utility.

While I have shown and described the preferred embodiment of my invention, I wish it to be understood that I do not confine myself to the precise details of construction herein set forth, by way of illustration, as it is apparent that many changes and variations may be made therein, by those skilled in the art, without departing from the spirit of the invention, or exceeding the scope of the appended claims.

I claim:

1. A device of the class specified comprising a heating vessel having a discharge opening therein, an exterior plug for the discharge opening, means to operate said plug, an interior plug for the discharge opening, and means linked with the first named means to seat said interior plug simultaneous with the seating of the exterior plug.

2. A device of the class specified comprising a heating vessel having a discharge opening therein, an exterior plug for the discharge opening, an interior plug for the discharge opening, and means for simultaneously effecting the seating of said plugs.

3. A device of the class specified comprising a heating vessel having a discharge opening therein, an interior plug for the discharge opening, a stem on which the plug is mounted extending through the heating vessel, and means coacting with the stem to normally keep the plug unseated.

4. A device of the class specified comprising a heating vessel having a discharge opening therein, an interior plug for the

discharge opening, a stem on which the plug is mounted extending through the heating vessel, a protecting tube through which the stem is adapted to reciprocate, and 5 means coacting with the stem to keep the plug normally unseated.

5. A device of the class specified comprising a heating vessel having a discharge opening therein, an interior plug for the 10 discharge opening, a stem on which the plug is mounted extending through the heating vessel, a base for the heating vessel, a lug on the stem without the heating vessel, and a compression spring between the 15 heating vessel base and the lug for normally keeping the plug unseated.

6. A device of the class specified comprising a heating vessel having a discharge opening therein, an interior plug for the 20 discharge opening, a stem on which the plug is mounted extending through the heating vessel, a base for the heating vessel, a lug on the stem without the heating vessel, a compression spring operating on said lug, 25 and resilient means for exerting a compression contra to that of the compression spring for seating the plug in the discharge opening.

7. A device of the class specified comprising 30 a heating vessel having a discharge opening therein, an interior plug for the discharge opening, a stem on which the plug is mounted extending through the heating vessel, a base for the heating vessel, a lug on 35 the stem below the base, a compression spring on the stem between the lug and the base of vessel, a second compression spring on the stem below the lug, and lever means for exerting compression through the second 40 mentioned compression spring to overcome the first mentioned spring and seat the plug in the discharge opening.

8. A device of the class specified comprising 45 a heating vessel having a discharge opening therein, an interior plug for said opening, a rod carrying said plug, resilient means acting on said rod a guide on the device in which the rod is adapted to reciprocate, and a manually controlled lever 50 on the device for reciprocating the rod to seat the plug in the discharge opening.

9. A device of the class specified comprising 55 a heating vessel having a discharge opening therein, an exterior plug for said opening, a rod carrying said plug, a guide on the device in which the rod is adapted to reciprocate, a cam member on the rod, a sealing stamp mechanism pivoted on the device, a cam on the sealing stamp mechanism 60 cooperating with the cam member whereby the rod is reciprocated to seat the plug in the discharge opening during a stamping operation.

10. A device of the class specified comprising 65 a heating vessel of electrically non-

conducting material having a discharge opening, double spiral grooves on the exterior thereof in proximity to the discharge end, an electrical resistance element wound in the double spiral grooves, and a detachable handle forming the base of the heating vessel. 70

11. A device of the class specified comprising a heating vessel of electrically non-conductive material having a discharge 75 opening, double spiral grooves in the exterior thereof in proximity to the discharge end, an electrical resistance element wound in the double spiral grooves, a detachable handle forming the base of the heating vessel, a heating insulating cover over the heating vessel, and an outer casing, said device having located near the back a vent through the outer casing, the heat insulating cover 80 and the heating vessel wall. 85

12. A device of the class specified comprising a heating vessel having a discharge outlet, double spiral grooves in the exterior thereof, an outer casing, heat insulating material around said double spiral grooves and 90 within the outer casing, and a vent extending through the outer casing, the heat insulating cover and the heating vessel wall.

13. A device of the class specified comprising a heating vessel having a discharge 95 outlet therein, a handle on said vessel an outer casing, heat insulating material between the casing and vessel, means operable from the handle to control the flow of heating material from the vessel, a detachable 100 handle forming a base for the vessel and short legs located in proximity to the discharge opening whereby the device may be supported and steadied in pouring. 105

14. A device of the class specified comprising a heating vessel having a discharge opening therein, a holder for cleansing material attached to the device near the discharge opening, and a sealing stamp rotatively mounted above the holder and normally in contact with the cleansing material whereby the stamp may be kept constantly cleansed for instant use. 110

15. A device of the class specified comprising a heating vessel having a discharge 115 opening therein, a holder for cleansing material attached to the device near the discharge opening, a sealing stamp rotatively mounted above the holder whereby the stamp may be kept constantly cleansed for instant use, a plug for the inside of the discharge opening, a plug for the outside of the discharge opening, a cam carried by the rotatively mounted sealing stamp mechanism, means cooperating with said cam 125 whereby the exterior and interior plugs will be seated during the stamping operation.

16. A device of the class specified comprising a heating vessel, an electrical resistance heating element for the heating vessel. 130

sel, a detachable handle for the heating vessel having a passageway therein for electrical conductors, a screw-plug for the exterior end of the passageway for guiding the conductors, and a supporting member integrally formed with the screw-plug for hanging up the device.

17. A device of the class specified comprising a heating vessel having a discharge opening therein, an interior plug for the discharge opening, a stem on which the plug is mounted extending through the heating vessel, means coacting with the stem to normally keep the plug unseated, an exterior plug for said opening, a rod carrying said plug, a guide on the device in which the rod is adapted to reciprocate, and a manually controlled thumb lever on the device whereby the rod and stem may be reciprocated to close the discharge opening from both the exterior and the interior.

18. A device of the class specified comprising a heating vessel having a discharge opening therein, an interior plug for the discharge opening, a stem on which the plug is mounted extending through the heating vessel, a protecting tube through which the stem is adapted to reciprocate, an exterior plug for said opening, a rod carrying said plug, a guide on the device in which the rod is adapted to reciprocate, a cam member on the rod, a sealing stamp mechanism cooperating with the cam member whereby the rod is reciprocated to seat the exterior plug, and means cooperating with the rod to cause the interior plug to seat.

19. A device of the class specified comprising a heating vessel having a discharge opening therein, an interior plug for the discharge opening, a stem on which the plug is mounted extending through the heating vessel, a protecting tube through which the stem is adapted to reciprocate, a base for the heating vessel, a lug on the stem below the base, a compression spring on the stem between the lug and the base, a second compression spring on the stem below the lug, an exterior plug for said opening, a rod carrying said plug, a guide on the device in which the rod is adapted to reciprocate, a cam member on the rod, a sealing stamp mechanism pivoted on the device, a cam on the sealing stamp mechanism cooperating with the cam member whereby the rod may be reciprocated to seat the plug, a lever means for exerting the pressure on the second mentioned compression spring to overcome the first mentioned compression spring and seat the interior plug simultaneously with the seating of the exterior plug.

20. A device of the class specified, comprising a heating vessel having a discharge opening therein, a holder for cleansing ma-

terial attached to the device near the discharge opening, short legs integrally formed with the holder, and a sealing stamp rotatively mounted above the holder and normally in contact with the cleansing material whereby the stamp may be kept constantly cleansed for instant use.

21. A device of the class specified comprising a heating vessel having a discharge opening therein, a holder for cleansing materials attached to the device near the discharge opening, a sealing stamp rotatively mounted above the holder and normally in contact with the cleansing material, a plug for the inside of the discharge opening, and means cooperating with the movement of the stamp to operative position to plug up the discharge opening.

22. A device of the class specified comprising a heating vessel, an electrical resistance element for heating said vessel, a detachable handle for the heating vessel having a passage-way therein, electrical lead-in conductors in said passage-way, and conductor compression springs in said handle connecting the electrical resistance element to the lead-in conductors.

23. A device of the class specified comprising a heating vessel having a discharge opening therein, double spiral grooves on the exterior of the vessel in proximity to the discharge end, an electrical resistance element wound in the double spiral grooves, electrical insulating material wrapped around the heating vessel and the electrical resistance mounted thereon, an interior plug for the discharge opening, a stem on which the plug is mounted extending through the heating vessel, a protecting tube through which the stem is adapted to reciprocate, an exterior plug for said opening, a rod carrying said plug, a guide on the device in which the rod is adapted to reciprocate, a cam member on the rod, a sealing stamp mechanism cooperating with the cam member whereby the rod is reciprocated to seat the exterior plug, means cooperating with the rod to cause the interior plug to seat, an outer casing, a heat insulating material placed between the outer casing and the electrical resistance and electrical insulation, a vent near the back of the device extending through the outer casing, the heat insulating cover and the heating wall, a detachable handle for the heating vessel having a passageway therein for the electrical conductors, a screw plug for the exterior end of the passageway for guiding the conductors, and a supporting member integrally formed with the screw plug for hanging up the device.

In testimony whereof I affix my signature.
JULE SCREVEN WILLCOX.
